(57) **CLAIM**

I claim the ornamental design for a toothbrush drive train, as shown.

DESCRIPTION

FIG. 1 is a front isometric view of a toothbrush drive train. FIG. 2 is a rear isometric view of the toothbrush drive train. FIG. 3 is a front elevation view of the toothbrush drive train. FIG. 4 is a rear elevation view of the toothbrush drive train. FIG. 5 is a left side elevation view of the toothbrush drive train. FIG. 6 is a right side elevation view of the toothbrush drive train. FIG. 7 is a top plan view of the toothbrush drive train; and, FIG. 8 is a bottom plan view of the toothbrush drive train.
